HAROLD O. OLSEN, OF WATERTOWN, NEW YORK.

SCREEN-COVERED CYLINDRICAL ROLL FOR PAPER-MAKING MACHINES.

1,196,389.

Specification of Letters Patent. Patented Aug. 29, 1916.

Application filed November 6, 1915. Serial No. 60,120.

To all whom it may concern:

Be it known that I, HAROLD O. OLSEN, a citizen of the United States of America, and resident of Watertown, in the county 5 of Jefferson, in the State of New York, have invented new and useful Improvements in Screen-Covered Cylindrical Rolls for Paper-Making Machines, of which the following, taken in connection with the accompanying 10 drawings, is a full, clear, and exact description.

This invention relates to certain improvements in screen covered cylindrical rolls for paper making machines, and refers more 15 particularly to means for fastening the screens to the cylinders to prevent buckling or wrinkling of the screen due to longitudinal or transverse creeping of the end edges thereof, more particularly while the cylinder 20 is in action. These screens are made in widths corresponding to the lengths of the cylinders to which they are to be applied and are cut in lengths corresponding to the circumference of such cylinders around 25 which they are tightly drawn, and their meeting ends firmly secured together to produce a smooth even surface.

In operation it is found that the ends of the screens tend to draw in from the heads 30 of the cylinder between the center thereof causing more or less wrinkling or buckling of the central portions thereof which not only produces excessive strain upon the screen, but produces corresponding impressions 35 in the paper, leaving the latter in a more or less mutilated or wrinkled condition, and, so far as I am aware, no adequate provision has yet been made to entirely obviate this difficulty.

40 The main object, therefore, is to provide a more expeditious and effective means for fastening the ends of the screen upon the cylinder so that all portions thereof will lie smoothly upon the periphery of the cylinder during the process of paper making in the machine in which the cylinder is employed, thereby assuring the production of 45 a better quality of paper by reducing the liability of impressing wrinkles or creases therein.

Other objects and uses relating to specific parts of the device will be brought out in the following description.

In the drawings Figure 1 is a face view

of a screen covered roll or cylinder embodying the features of my invention. Fig. 2 is an enlarged sectional perspective view of one end of the same roll or cylinder. Fig. 3 is a detail sectional view through a portion of one end of the cylinder showing the 5 method of threading the screen fastener through one of the dowels. Fig. 4 is a perspective view of a portion of the detached wire fastener for the screen as it appears when threaded through the dowels and 10 screens.

The cylinder may be of any suitable length or diameter and preferably comprises 15 end heads —1— connected by spokes —2—, to a hub —3— which is secured to a shaft —4—, the end heads being connected by dowels —5—, preferably of brass, arranged circumferentially about the axis of the shaft in parallelism and in uniformly spaced relation relatively short distances apart and 20 having their ends seated in suitable sockets in the heads —1— which serve to hold them in fixed relation lengthwise of the cylinder 25 and parallel with the axis thereof.

A screen —6— of comparatively coarse 30 mesh and of substantially the same axial width and circumferential length as the cylinder between the end heads —1— is wrapped tightly around and upon the outer faces of the dowels —5—, and its meeting 35 ends suitably secured together to form a substantially smooth supporting base for an outer screen —7— of relatively fine mesh. This outer screen —7— is of substantially 40 the same dimensions as the inner screen —6— and is tightly wrapped on the periphery thereof and its ends permanently joined together to form a substantially 45 smooth exterior surface in so far as it is free from wrinkles or buckling and together with 50 the inner supporting screen constitutes what may be termed a laminated foraminous drum of circular cross section tightly 55 wrapped around and upon the outer faces of the dowels and extending the entire 60 length of the space between the end heads of the cylinder. The opposite ends of this laminated screen drum are firmly secured to the adjacent portions of the dowels, preferably 65 by means of wire fasteners —8—, 70 each fastener preferably consisting of a single piece of wire threaded through radial 75 apertures —9— in successive dowels from 80 85 90 95 100 105

a predetermined point through and across the outer face of adjacent portions of the screen drum, said wires being drawn tightly during the threading process to firmly bind 5 the screen to the outer surfaces of the dowels against relative endwise or circumferential movement, and the ends of each wire which are finally at the point of beginning are twisted firmly together as at —10— to hold 10 them against loosening and thereby retaining the screen drum in place.

As illustrated, each end of each dowel near the adjacent end head —1— is provided with a pair of radial apertures —9— spaced 15 longitudinally a suitable distance apart to permit the adjacent wire fastener to be drawn through both apertures of each dowel and also through and across the outer face of the adjacent portion of the screen drum, 20 thereby affording two points of attachment of the screen to each dowel.

In practice the end of each wire fastener is threaded from the inside through one of the apertures, preferably the inner one, of 25 one of the dowels and through the portion of the screen aligned with that apertured, the end of the wire being then drawn still farther through the periphery of the screen across the outer face thereof and reentered 30 through the other aperture of the same dowel, thus producing a loop or staple binding the adjacent portion of the screen to that particular dowel, whereupon the same end of the wire fastener is drawn circumferentially and entered through the corresponding aperture of the next adjacent dowel and contiguous portion of the screen 35 to the exterior thereof and then returned across the face of the screen and reentered through the other aperture of the second dowel, thus forming another loop or staple binding the adjacent portion of the screen to the second dowel. This operation is 40 repeated through the apertures of successive dowels and through the contiguous portions of the screen until the advance end of the wire fastener is returned to the point of beginning where it is twisted at —10— to the other end in the manner just previously described, thus producing a circumferential 45 series of wire loops or staples —8'— running relatively short distances lengthwise of the drum in uniformly spaced relation circumferentially corresponding to the spacings of the dowels so that each end of the 50 drum is fastened to each dowel by a lengthwise loop or staple and by making the wire fastener at each end of the drum continuous, the prongs of the loops or staples which 55 are passed through the dowels and adjacent portions of the screen drum will be connected to each other across the space between the dowels. That is, the outer end of the prongs of the same staple will be 60 connected to the corresponding end of the 65

next adjacent prong at the other side, and when each wire fastener is drawn tightly during the process of threading it through successive dowels and adjacent portions of the screen, it is evident that the ends of the 70 screen drum will be firmly secured to the outer face of the dowels to prevent any possibility of creeping of the screens upon the dowels either longitudinally or circumferentially, the result of which will be to keep 75 the periphery of the screen drum substantially smooth or free from wrinkles or buckling throughout its entire area. It is also evident that by fastening each end of the screen to each dowel at two points of attachment in spaced relation lengthwise of the dowel, the liability of excessive shearing strain upon either point of attachment will be materially reduced, thereby prolonging 80 the life of the screen and fastener and, therefore, increasing the period of usefulness of 85 the entire cylinder.

The exposed portions of the loops or staples —8'— at the periphery of the drum are covered by bands —11— of fabric or 90 equivalent material commonly known as "decker" bands to protect them from excessive wear by contact with external objects, it being understood that the working face of the drum across which the paper is 95 fed is located between these "decker" bands.

The apertures in the dowels through which the wire fasteners are passed are of just sufficient size to receive the same, thereby additionally holding the screen 100 drum against relative endwise or circumferential movement.

What I claim is:

1. A cylindrical mold for paper making machines comprising end heads, a circumferential series of dowels connecting said heads, each end of each dowel having a pair of radial apertures therethrough in spaced relation lengthwise thereof, a screen drum drawn tightly around and upon the dowels 105 between the heads, and wire fasteners passed through the apertures in each dowel and through the adjacent portions of the screen 110 drum.

2. A cylindrical mold for paper making 115 machines comprising opposite circular end heads, a circumferential series of dowels connecting said heads and spaced uniform distances apart circumferentially, each end of each dowel being provided with a pair of apertures therethrough in spaced relation lengthwise thereof, a screen drum drawn tightly around and upon the outer faces of the dowels, and wire loops passed through the apertures of their corresponding dowels 120 and engaging the outer faces of adjacent portions of the screen drum, adjacent loops 125 being connected to each other at one end at the inner sides of the dowels.

3. In a cylindrical mold of the character 130

described, the combination of end heads, dowels connecting said heads and spaced circumferentially uniform distances apart about the axis of the cylinder, a screen drum wound tightly around and upon the dowels between the heads, and wire fastening devices passed through apertures in successive dowels and through and across the outer

faces of adjacent portions of the screen drum for securing said drum to the dowels.

In witness whereof I have hereunto set my hand this 28th day of October, 1915.

HAROLD O. OLSEN.
